US00D626246S

(12) **United States Design Patent**
Rees et al.

(10) **Patent No.:** US D626,246 S
(45) **Date of Patent:** ** Oct. 26, 2010

(54) **BABY BOTTLE WITH HANDLES**

(75) Inventors: **Arnold Rees**, Newcastle upon Tyne (GB); **Ian Webb**, London (GB); **Tom Cotton**, London (GB); **Mark Armstrong**, Gwynedd (GB)

(73) Assignee: **Jackel International Limited**, Cramlington, Northumberland (GB)

(**) Term: **14 Years**

(21) Appl. No.: **29/315,775**

(22) Filed: **Jul. 22, 2009**

Related U.S. Application Data

(63) Continuation of application No. 11/630,864, filed on Sep. 20, 2007.

(51) **LOC (9) Cl.** 07-01

(52) **U.S. Cl.** D24/197

(57) **CLAIM**

The ornamental design for a baby bottle with handles, as shown and described.

DESCRIPTION

FIG. 1 is a front elevation view of a baby bottle, wherein the front and the back of views of the bottle are identical;

FIG. 2 is side elevation view of the bottle of FIG. 1, wherein both sides of the bottle are identical;

FIG. 3 is an enlarged top plan view of the bottle of FIG. 1; and,

FIG. 4 is an enlarged bottom plan view of the bottle of FIG. 1. The broken lines in the drawings represent environmental subject matter and form no part of the claimed design.

1 Claim, 4 Drawing Sheets
